UNITED STATES PATENT OFFICE.

MELVIN W. KAYE, OF MONACA, PENNSYLVANIA.

BODY-REST.

1,238,782.

Specification of Letters Patent. Patented Sept. 4, 1917.

Application filed January 30, 1917. Serial No. 145,349.

To all whom it may concern:

Be it known that I, MELVIN W. KAYE, a citizen of the United States of America, residing at Monaca, county of Beaver and State of Pennsylvania, have invented certain new and useful Improvements in Body-Rests, of which the following is a specification.

This invention relates to a detachable and collapsible body rest adapted for use in connection with seats, chairs, and benches, more particularly railway car seats, and has for its object to provide means, in a manner as hereinafter set forth, capable of being detachably secured in an upright position at one end of a seat or bench for squarely, comfortably and efficiently supporting the body of a person when one is reclining in a direction corresponding to the direction of length of seat.

A further object of the invention is to provide a rest for the purpose set forth having means to permit of extending the height thereof to provide for different heights of chair or bench backs when the rest is used.

A further object of the invention is to provide a rest for the purpose set forth having bracing means capable of being detachably connected with a window sill, or other support, for maintaining the rest in an upright position.

A further object of the invention is to provide a rest for the purpose set forth, in a manner as hereinafter referred to, whereby the elements forming the rest can be disconnected from each other and folded in a compact manner.

Further objects of the invention are to provide a rest for the purpose set forth which is simple in its construction and arrangement, strong, durable, efficient in its use, readily set up and inexpensive to manufacture.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications

can be resorted to which come within the scope of the claims hereunto appended.

In the drawings wherein like reference characters denote corresponding parts throughout the several views:—

Figure 1 is a perspective view of a car seat and a portion of a window showing the adaptation with the window sill of a rest in accordance with this invention.

Fig. 2 is an elevation of a rest in accordance with this invention.

Fig. 3 is a top plan view of the rest.

Fig. 4 is a sectional detail of one of the telescopic uprights.

Fig. 5 is an elevation of a brace.

Figs. 6 and 7 are details illustrating a clamping means for the lower brace member.

Fig. 8 is a detail illustrating a connection between one end of a cross member and an upright.

Referring to the drawings in detail 1 denotes a railway car seat which includes a back 2 and end or side rails 3. 4 denotes a window-sill. The foregoing elements are of known construction.

The rest comprises a pair of uprights each of which consists of an upper section 5, and a lower section 6. The section 5 is hollow and the section 6 telescopes therein. The lower end of the section 5 is split, as at 7, and also provided with peripheral threads 8. The upper portion of the section 6 is threaded as at 6a.

The section 6 is maintained from movement relatively to the section 5 by a clamping nut 9, which engages the peripheral threads 8 and owing to the fact that the lower portion of the section 5 is slotted, when the nut 9 is moved upon the section 5, the lower end thereof is frictionally clamped to the section 6.

When the lower portion of the section 5 is clamped to the threaded portion of the section 6, the threads 6a prevent any slipping of the sections relatively to each other, or in other words cause a more binding engagement when the clamping nut 9 is set to clamp the sections 5 and 6 together.

As the sections 5 and 6 of each upright are capable of shifting relatively one to the other, it is obvious that the height of

the rest can be regulated as desired. The inner side of each section 5, near the top thereof, is formed with a series of inwardly extending lateral lugs 10, 11 and 12 and each of said lugs is formed with a triangular shape recess 13 and a slot 14 which communicates with the recess 13.

Each of the sections 5, near its lower end, has a pair of inwardly extending lugs 15 formed in a manner similar to either of the lugs 10, 11 and 12. The lugs 15 are arranged above the slotted lower portions 7 of the section 5. One of the sections 5 below the lug 12 is provided with a lug 16 which is disposed at right angles with respect to the lug 12 and provided with a pocket 17.

The uprights are connected together and maintained in spaced relation by a pair of curved brace members 18, 19. The former is arranged near the top of the uprights and the latter intermediate the ends of the uprights. The member 18 is utilized for supporting the head and the member 19 for the back and said member 18 is formed with a series of dove-tail tongues 20 which detachably engage in the recess and lugs 10, 11 and 12. The member 19 is formed with dove-tail tongues 21 which detachably engage in the lugs 15.

When the members 18, 19, are coupled with the uprights, vertical movement is arrested, by split rings 22 and 23. The former surrounds an upright near its upper end 35 and is interposed between the lugs 11 and 12 and the latter surrounds the lower portion of the section 5 of an upright and is interposed between the pair of lugs 15. In case the member 18 moves upwardly its 40 movement is arrested by the abutting of the ring 22 against the lug 11 and if the member 19 moves upwardly the shifting movement thereof is arrested by the ring 23 abutting against the upper lug 15.

45. When the uprights are coupled together by the members 18 and 19 and arranged in vertical position, such position is maintained, by elements consisting of a lengthwise adjustable sectional rod 24, pivoted 50 as at 25, to an ear 26, projecting from a tongue 27 which is capable of engaging in the lug 16. The sections of the rod 24 are maintained in an adjusted position by a clamping nut 28. The lower end of the rod 24 is bent at right angles as at 29 and is adapted to seat upon a window-sill 4. Extending downwardly through the right angular end 29 of the rod 24 is a hook 30 capable of engaging against the lower face of 60 the sill 4. The hook 30 is maintained in clamping position by a thumb-nut 31, which is mounted on the shank of the hook and engages the right angular end 29 of the rod 24. A washer 32 or other suitable means, is 65 carried by the right angular end 29 of the

rod 24 to prevent said end from injuring the sill 4.

Near the lower end of the rod 24 a forwardly projecting ear 33 is provided, to which is pivotally connected as at 34, a brace 70 rod 35, the latter having its lower end terminate in a clamp section 36. Pivotally connected, as at 37, to the rod 35 is a clamping section 38. The clamping section 36 has a locking device 39 which when swung to 75 engage the section 38 will maintain said clamping sections around the section 6 of an upright as indicated in Fig. 2.

The reference character 40 denotes a strip of canvas or other suitable means which is 80 arranged against the members 18 and 19.

Each of the sections 5 has a screw threaded extension 41 with which is adapted to engage a crook 42 which takes over the top 85 of the back of the seat.

When the rest is in operative position the crook 42 takes over the back edge of the seat, the uprights are mounted upon the seat bottom and the brace element is connected with the sill 4, or other suitable 90 anchoring means and by such an arrangement the rest is maintained in a perpendicular position.

Owing to the manner in which the elements of the rest are set up it is obvious 95 that they can be disconnected from each other after which the rest can be folded in a compact manner. Preferably the canvas or cover 40 is employed to inclose the elements of the rest when they are detached 100 from each other.

What I claim is:—

1. A rest for the purpose set forth comprising a pair of extensible uprights, curved brace members detachably connected with 105 said uprights for maintaining them in spaced relation with respect to each other, and an element adapted to be detachably connected to an anchoring device and further detachably connected near the upper and the lower 110 end of the upright.

2. A rest for the purpose set forth comprising a pair of extensible uprights, curved brace members detachably connected with 115 said upright for maintaining them in spaced relation with respect to each other, and an element adapted to be detachably connected to an anchoring device and further detachably connected near the upper and the lower 120 end of an upright, and a crook detachably connected to the upper end of one of said uprights.

3. A rest for the purpose set forth comprising a pair of extensible uprights, curved brace members detachably connected with 125 said uprights for maintaining them in spaced relation with respect to each other, and an element adapted to be detachably connected to an anchoring device and further detachably connected near the upper and the 130

lower end of an upright, and a crook detachably connected to the upper end of one of said uprights, said anchoring element including an extensible rod.

5 4. A device for the purpose set forth comprising a pair of uprights, brace members detachably connected with said uprights for maintaining them in spaced relation with respect to each other, a brace element including an upper and a lower rod hinged together, means carried by an upright and by said upper rod for detachably connecting said rod to the upper portion of said upright, means carried by the lower rod for 10 detachably clamping it near the lower end of said upright, and means carried by the lower end of the upper rod for anchoring said brace member.

5. A device for the purpose set forth comprising a pair of uprights, brace members detachably connected with said uprights for maintaining them in spaced relation with respect to each other, a brace element including an upper and a lower rod hinged together, means carried by an upright and by said upper rod for detachably connecting said rod to the upper portion of said upright, means carried by the lower rod for detachably clamping it near the lower end of said upright, and means carried by the lower end of the upper rod for anchoring said brace member, each of said uprights being extensible.

6. A device for the purpose set forth comprising a pair of uprights, brace members detachably connected with said uprights for maintaining them in spaced relation with respect to each other, a brace element including an upper and a lower rod hinged together, means carried by an upright and by said upper rod for detachably connecting said rod to the upper portion of said upright, means carried by the lower rod for detachably clamping it near the lower end of said upright, and means carried by the lower end of the upper rod for anchoring said brace member, and a crook capable of

being carried by the upper end of either of said uprights for connecting the upright with the back of a seat.

50

7. A device for the purpose set forth comprising a pair of uprights, brace members detachably connected with said uprights, for maintaining them in spaced relation with respect to each other, a brace element including an upper and a lower rod hinged together, means carried by an upright and by said upper rod for detachably connecting said rod to the upper portion of said upright, means carried by the lower rod for 60 detachably clamping it near the lower end of said upright, and means carried by the lower end of the upper rod for anchoring said brace member, and a crook capable of being carried by the upper end of either of 65 said uprights for connecting the upright with the back of a seat, said upper rod being extensible.

65

8. A device for the purpose set forth comprising a pair of uprights, brace members detachably connected with said uprights, for maintaining them in spaced relation with respect to each other, a brace element including an upper and a lower rod hinged together, means carried by an upright and by 70 said upper rod for detachably connecting said rod to the upper portion of said upright, means carried by the lower rod for detachably clamping it near the lower end of said upright, and means carried by the 75 lower end of the upper rod for anchoring said brace member, and a crook capable of being carried by the upper end of either of 80 said uprights for connecting the upright with the back of a seat said upper rod being extensible, each of said uprights being extensible, and means for clamping each upright in adjusted position.

85

In testimony whereof I affix my signature in the presence of two witnesses.
